UNITED STATES PATENT OFFICE.

MICHAEL REDLINGER AND MATTHIAS REDLINGER, JR., OF FREEPORT,
ILLINOIS.

CORK-EXTRACTOR.

SPECIFICATION forming part of Letters Patent No. 546,747, dated September 24, 1895.

Application filed July 5, 1895. Serial No. 555,023. (No model.)

To all whom it may concern:

Be it known that we, MICHAEL REDLINGER and MATTHIAS REDLINGER, Jr., citizens of the United States, residing at Freeport, in the county of Stephenson and State of Illinois, have invented certain new and useful Improvements in Cork-Extractors, of which the following is a specification, reference being had therein to the accompanying drawings.

Figures 1 and 2 are side and front views, respectively, of mechanism embodying our improvements. Fig. 3 is a side view of a bracketed standard serving as the foundation or stationary portion of the machine.

Figs. 4 and 5 are views of the interior of the bottle-carriage of the extractor, having operative devices, that will be fully described hereinafter, mounted therein. Fig. 6 is a view of the extractor with the portion Fig. 5 of the bottle-carriage thereof removed. Fig. 7 is a front view of parts shown in Fig. 6 with the portion Fig. 4 of the bottle-carriage thereof sectioned at the dotted line 7 in Fig. 6. Fig. 8 is a view of the parts shown in Fig. 7 with the corkscrew-nut at its upper limit. Fig. 9 is a section at the dotted line 9 in Fig. 4 with parts added, to which reference will be made when explaining the mode of operating the extractor. Fig. 10 is a side view of the extractor, a part of its bottle-carriage having been removed, showing in full lines the relative positions of its parts just as the corkscrew has completed a traverse into a cork in a bottle. The dotted lines therein indicate

the positions assumed by the parts of the extractor and the bottle, just as the cork has left the latter. Fig. 11 is an edge view of a cam-disk. Fig. 12 is a side view of a corkscrew-nut. Fig. 13 is a side view of a corkscrew-nut carrier. Fig. 14 is a view of the back edge of the same. Figs. 15 and 16 are bottom plan views of the jaws of the extractor open and closed, respectively.

Like letters of reference indicate corresponding parts throughout the several views. A is a standard, terminating at its upper end in a bracket, having a vertical arm A' and a horizontal arm A², with a horizontal cam-groove A³ and a vertical recess A⁴ therein

and horizontal transverse lugs A⁵ A⁶, having a circular bearing A⁷ and a conical bearing A⁸ therein, projecting therefrom. The standard A is also provided with vertical ways A⁹ and clamping-jaws A¹⁰ A¹¹, the latter furnished with a thumb-screw A¹².

B is a corkscrew, rotatably mounted by its upper end in the circular bearing A⁷ in the lug A⁵ and terminating above in a cone B', having a conical bearing A⁸ in the under side of the lug A⁶.

C is a corkscrew-nut, threaded to receive the corkscrew B, whereon it is adapted to freely slide.

C' C² are vertical and horizontal slots in the corkscrew-nut.

D is a corkscrew-nut carrier connecting with the corkscrew-nut C by means of the T-head D' and the slots C' C² therein, terminating at its upper end in a lug D², adapted to engage with and be disengaged from the cam-groove A³ in the bracket-arm A² and tapered toward its back edge D³.

E is one portion of a bottle-carriage and is recessed to admit the vertical and horizontal bracket-arms A' A², the parts connected therewith and supported thereby, and a cam-disk to be described hereinafter. E' is also a portion of the bottle-carriage and serves as a cover for the part E thereof. The parts E E' are provided with guide-lugs E² E³ projecting therefrom into the vertical ways A⁹ in the standard A, wherein they freely slide.

F is an oscillatory disk provided with cams F' F² on the edge thereof and having a depressed portion F³ therein.

G is a short rock-shaft, mounted in the part E of the bottle-carriage, rigidly connected at one end with the oscillatory cam-disk F and at the other end with the operating-lever H of the extractor.

I is a wheel mounted by means of a stud-bearing I' on the inner face of the oscillatory cam-disk F eccentrically therewith and adapted to travel back and forth in the cam-groove A³ in the bracket-arm A².

J, Fig. 4, is a recess in the part E of the bottle-carriage to receive the upper portion of the corkscrew-nut carrier D when the cork-

screw-nut C is at its lowest position, as in Fig. 7, the part E in this figure being, however, so sectioned away as not to contain the recess J.

K, Figs. 4 and 7, is a spring normally impelling the corkscrew-nut carrier D toward the corkscrew B.

L L' are jaws for grasping the necks of bottles from which corks are to be extracted, are lined with rubbers L² L³, and are supported by arms L⁴ L⁵, which are hinge-jointed by their upper ends to the parts E E' of the bottle-carriage.

M M' are springs mounted in the parts E E' of the bottle-carriage and provided with arms M² M³, the outer ends whereof are hinge-jointed to lugs L⁶ L⁷ on the jaws L L'. When the force of the springs M M' is acting in front of X, Figs. 1, 15, and 16, they normally hold the jaws L L' tightly closed. When it is acting in the rear of X, it normally holds them open, as at Fig. 15.

Our cork-extractor is operated as follows: The operator places his hand upon the back of the jaws L L', as at X in Fig. 1, and draws them forward toward the lever H, when they will open, as in Fig. 15. Then place the neck of the bottle to be uncorked in the center of the jaws L L' and give it a push, whereupon the jaws will close and firmly grasp the bottle, as in Figs. 10 and 16. Supposing the parts of the extractor to be in the positions shown in Fig. 6, then move the lever H from the position shown in Fig. 6 to that shown in Fig. 10. The last-mentioned operation will elevate the bottle-carriage E E' to the position shown in Fig. 10, thereby causing the corkscrew B to enter and traverse the cork N in the bottle N'. As the bottle-carriage E E' went up to the position shown in solid lines in Fig. 10, the upward pressure of the cork in the bottle forced the corkscrew-nut C and the corkscrew-nut carrier D from the positions shown in Figs. 6 and 7 to the positions shown in Figs. 8 and 10, whereupon the spring K, Figs. 4 and 7, caused the lug D² on the corkscrew-nut carrier D to engage with the cam-groove A³ in the arm A², and thus leave the corkscrew-nut C suspended thereby. If the lever H be now further depressed to the position shown in Fig. 1 and indicated by dotted lines in Fig. 10, the carriage E E' will descend to its original position, the position indicated by dotted lines in Fig. 10, and the cork will have been completely withdrawn from the bottle, and the corkscrew C and corkscrew-nut carrier D will be in the positions shown in Figs. 8 and 10, with the corkscrew B inserted in the cork N, as in Fig. 10. The bottle N' is next grasped by the operator and pulled gently forward, thereby opening the jaws L L', Fig. 15. If the lever H be now moved from the position shown in Figs. 1 and 2 and indicated by dotted lines in Fig. 10 to the position shown in Fig. 4, the cam F', Fig. 9, on the cam-disk F, will travel upward and engage

with the free end of the corkscrew-nut carrier D, guiding it in between the outer face of the cam-disk F and the inside face of the part E of the bottle-carriage, Figs. 6 and 7, thereby withdrawing the lug D² from engagement with the cam-groove A³ in the horizontal arm A², and as the lever H continues to travel backward to the position shown in Fig. 6 the corkscrew-nut carrier D and its corkscrew-nut C will be forced down to the positions shown in Figs. 6 and 7, which last operation discharges the cork from the corkscrew B and leaves the extractor with all its parts in position to receive another bottle to be uncorked.

80

We claim—

1. In a cork extractor, in combination, a standard terminating at its upper end in a horizontal arm, a cork screw rotatably mounted by its upper end in a stationary bearing therein, a cork screw nut corresponding with, and adapted to freely slide up and down upon, the cork screw, an oscillatory cam disk for driving the cork screw nut, and a cork screw nut carrier connecting the oscillatory cam disk with the cork screw nut, substantially as and for the purpose specified.

2. In a cork extractor, in combination, a standard terminating at its upper end in a bracket having a cam groove in the horizontal arm thereof, a bottle carriage adapted to travel vertically on the bracket, an oscillatory cam disk mounted in the bottle carriage and a wheel—mounted on the inner face of the oscillatory cam disk eccentrically therewith—engaging with and adapted to travel back and forth in the cam groove in the horizontal bracket arm, substantially as and for the purpose specified.

3. In a cork extractor, in combination, a main frame, jaws, for grasping the necks of bottles, hinge jointed at their rear portions and provided with supporting arms, hinge jointed by their upper ends to the main frame, and springs for actuating the jaws, substantially as and for the purpose specified.

4. In a cork extractor, in combination, a standard terminating at its upper end in a bracket having a cam groove in the horizontal arm thereof, a cork screw rotatably mounted by its upper end in the horizontal bracket arm, a bottle carriage provided with spring actuated jaws for grasping the necks of bottles and adapted to travel up and down the vertical arm of the bracket, an oscillatory cam disk mounted in the bottle carriage and a wheel—mounted on the inner face of the oscillatory cam disk eccentrically therewith—engaging with and adapted to travel back and forth in the cam groove in the horizontal bracket arm, substantially as and for the purpose specified.

5. In a cork extractor, in combination, a standard terminating at its upper end in a bracket having a cam groove in the horizontal arm thereof, a cork screw rotatably mount-

110

105

115

120

ed by its upper end in the horizontal bracket arm, a cork screw nut corresponding with, and adapted to freely slide upon, the cork screw, a cork screw nut carrier, connected with the cork screw nut, a bottle carriage adapted to travel up and down the vertical arm of the bracket, and an oscillatory cam disk mounted in the bottle carriage and connecting with the

cam groove in the horizontal bracket arm and with the cork screw nut carrier, substantially as and for the purpose specified

MICHAEL REDLINGER.
